J. HACKETT.

WATER GAGE.

APPLICATION FILED MAR. 27, 1911.

Patented May 14, 1912.

UNITED STATES PATENT OFFICE.

JAMES HACKETT, OF PORT COSTA, CALIFORNIA.

WATER-GAGE.

1,026,309.

Specification of Letters Patent.

Patented May 14, 1912.

Application filed March 27, 1911. Serial No. 617,223.

To all whom it may concern:

Be it known that I, JAMES HACKETT, citizen of the United States, residing at Port Costa, in the county of Contra Costa and State of California, have invented new and useful Improvements in Water-Gages, of which the following is a specification.

This invention relates to a water gage such as is employed on steam boilers for indicating the depth of water therein.

It is the object of this invention to provide a water gage which is so constructed and arranged that the steam entering the top thereof will be delivered to the glass tube some distance below its upper terminal, thereby preventing extreme heating of the glass adjacent its upper end, which, in many instances, results in the bursting of the tube.

Another object is to provide a water glass with valved inlets which are adapted to be quickly shut off in the event of accidental breaking of the glass tube.

The invention consists of the parts and the combination and construction of parts as hereinafter more fully described and claimed, having reference to the accompanying drawings, in which—

Figure 1 is a front elevation of the invention. Fig. 2 is a vertical section on the line *a—a*, Fig. 1. Fig. 3 is a transverse section on the line *y—y*, Fig. 2.

In the drawings, *A* represents a transparent glass tube, which is slidably supported at its upper and lower ends in packing glands *2—3*, respectively, which glands are screw-threaded on valve-casings *4—5*, and press packing rings *6—6'* against the outer surface of the tube *A*. The ends of the tube *A* extend a short distance into the valve casings *4—5* and are held out of contact therewith by means of the packing rings *6—6'* so that there will be no metal touching the glass tube at any point.

The essence of this invention resides in forming a cylindrical chamber *a* in the valve casing *4* above the upper end of the tube *A*, on the walls of which chamber an offset or shoulder *7* is formed, and inserting a baffle disk *8* therein. The disk *8* is designed to rest on the offset *7* and has a downwardly projecting flange *9* which touches the inner wall of the chamber below the offset *7*.

Formed on the underside of the disk *8* is a tubular member *10*, which extends some distance downward into the glass tube *A* out of contact therewith. This tube *10* is

open at its lower end to the interior of the tube *A* and opens at its upper end to the chamber above the baffle disk *8*. The disk *8* is held in place on the offset *7* by means of a cap *11* which is threaded in the chamber above the disk *8* and forms a closure therefor, this cap having a downwardly projecting flange *12* which is adapted to contact with the upper face of the disk *8* and a wrench hold *13*, by means of which it may be screwed in place or readily removed. The lower edge of the flange *12* on the cap *11* is provided with a peripheral groove *14*, which extends entirely around the exterior of the flange to form an annular passage between the flange and the walls of the chamber adjacent the disk *8*. A series of perforations *15* is formed in the flange *12* so as to render the passage *14* and the space inside the flange *12* intercommunicative, and thereby permit the passage of steam from a port *16* in the valve casing to the space above the baffle disk *8*. The port *16* communicates with the interior of a valve chamber *17* in which is seated a valve *18*, mounted on a valve stem *19*, extending through a stuffing box *20* at right angles to the valve casing *4*, the valve chamber *17* opening to a boiler through a port *21* in a nipple *22*. The valve stem *19* is provided with a lever handle *23*, by the operation of which the valve *18* may be moved to open or close the port *16*.

Mounted in the lower valve casing *5* is a cut-off valve *18'* constructed and mounted the same as the cut-off valve *18* in the upper casing *4*, this valve being provided to open or close ports *16'—21'* communicating with the lower end of the glass tube *A* and the interior of a boiler. A nipple *22'* is formed on the valve casing *5* by means of which it may be attached to a boiler in the usual manner.

When the valves *18—18'* are open, water and steam will enter the glass tube, the water entering through the port *16'* and the steam passing through the port *16*, passage *14*, and perforations *15* into the space above the baffle disk *8*, thence downward through the tube *10*, and being discharged into the glass tube *A* below the valve casing *4*. This manner of directing the steam into the tube *A* constitutes an important feature of this invention, inasmuch as the hot, dry steam is prevented from coming in contact with that portion of the glass tube *A* which extends into the valve-casing *4*, it being well

known that the heat of the upper valve casing in common water gages is transmitted to the upper ends of the glass tube therein so that the tube is worn off by the contact of the dry steam therewith. This, in time, results in the bursting of the tube.

From the foregoing it will be seen that in the event that the glass A becomes broken, the valves 18-18' may be readily closed by 10 operating the levers 23-23', which may be done from a distance by any suitable means, not shown. When it is desired to remove or replace a tube A, the cap 11 and the disk 8 are removed from the casing 4, and the 15 glands 2-3 are loosened, which permits of the ready removal or insertion of the tube.

Having thus described my invention, what I claim and desire to secure by Letters-Patent, is—

20 1. In a water gage, the combination of a valve casing having a chamber and having an internal shoulder, a glass tube mounted in said casing, a baffle plate disposed in said casing above the tube and having a flange 25 engaging said shoulder, means on said plate for directing steam through the plate to the interior of the tube some distance below the upper end thereof, a cap fitting the casing and having a flange with openings to a space above said disk, and to the chamber of the casing, said casing having a port, and a 30 valve for closing said port.

2. In a water gage, the combination of a valve casing, having a chamber and having

an internal shoulder, a glass tube mounted 35 in said casing, a baffle plate disposed in said casing above the tube and having a flange engaging said shoulder, means on said plate for directing steam through the plate to the interior of the tube some distance below the 40 upper end thereof, a cap fitting the casing and having a flange with openings to a space above said disk and to the chamber of the casing, said casing having a port, and a valve for closing said port, said valve having 45 a stem, and a lever thereon for operating the valve.

3. In a water gage, the combination with a valve casing, and a glass tube supported at its upper and lower ends therein, of a metallic tube extending into the upper end of the glass tube, a baffle plate mounted in the upper valve casing on which plate said tube is formed, and a cap fitting the upper casing and having a flange engaging the plate from 50 above, said flange being of reduced thickness at one end to form a circumscribing space between itself and the inner wall of the casing, and said flange having openings forming a connection between said space and said 55 tube.

In testimony whereof I have hereunto set my hand in the presence of two subscribing witnesses.

JAMES HACKETT.
